UNITED STATES PATENT OFFICE.

SAMUEL M. COFFMAN, OF KANSAS CITY, MISSOURI, ASSIGNOR TO OLD WORLD PARFUM CO., OF KANSAS CITY, MISSOURI, A CORPORATION OF MISSOURI.

PERFUME-VENDING MACHINE.

Original application filed November 9, 1925, Serial No. 67,943. Divided and this application filed January 10, 1927. Serial No. 160,183.

This invention relates to coin-controlled perfume or other liquid discharging machines of that class in which the deposit of a coin of proper size enables the depositor 5 to operate the machine and effect the discharge of a small quantity of liquid in atomized condition, and my object is to produce an efficient machine of this character of simple, strong, durable and relatively inexpensive construction. This application forms a divisional application of my copending case for perfume vending machine, filed November 9, 1925, Ser. No. 67,943.

With the general object named in view, 15 the invention consists in certain novel features of construction and combinations of parts as hereinafter described and claimed; and in order that it may be fully understood, reference is to be had to the accompanying 20 drawings, in which:—

Figure 1 is a front view of the operative mechanism of a machine embodying the invention.

Figure 2 is a side elevation of the machine as disclosed by Figure 1.

Figure 3 is a vertical section taken on the line III—III of Figure 1.

Figure 4 is a plan view.

Figure 5 is a section on the line V—V 30 of Figure 1.

Referring to the drawings in detail, 1 indicates a support for the operative mechanism, said support being preferably in the form of a suitable cabinet into which the 35 coins drop and are retained until withdrawn by an authorized person. A vertical cylinder 2 is secured upon the support and provided with a top closure or cap 3, and rising from said cap at one side of the axial 40 center thereof is a standard 4 in which is mounted at one end a stationary shaft 5. The shaft where it extends through the standard is threaded, and to anchor it securely has an enlargement 6 to bear against 45 one side of the standard and a nut 6^a upon the shaft, bears against the opposite side of the standard.

Arranged vertically is a forked bar 7, 50 guided on enlargement 6 and provided with a stem 8 extending through the cap 3, and provided at its lower end with a piston or plunger 9 within the cylinder, a coil spring 10 fitting around said stem and exerting force against the cap and piston for the pur-

pose of holding the forked bar yieldingly 55 depressed to its fullest extent, as shown clearly by Figure 3. The piston has a valve seat orifice 11 engaged by a ball valve 12 seated under the pressure of a spring 13 carried by the piston, the arrangement being 60 such that upward movement of the piston results in the unseating of the valve under the air pressure developed, to permit air to pass through the orifice to the lower end of the cylinder, so that when the piston is moved downward and the valve is therefore seated, air will be forced from the cylinder 65 through an opening 14 thereof, for a purpose which hereinafter appears.

Projecting upward and rigid with the cap 70 3 is a post 15 having an upward arcuate extension 16 grooved at its inner side as at 17, and in the vertical plane of the groove 17 is a coin tube comprising a downward 75 and rearward sloping section 18 and a vertical depending section 19 for discharging the coins into the cabinet through the support 1.

The shaft 5 is disposed axially with respect to the arcuate post extension 16, and journaled on said shaft is a peripherally 80 grooved wheel 21 provided at diametrically opposite points with peripheral coin pockets 22. Said wheel is also provided with a pair of diametrically opposite rollers 23 for alternate engagement with a crosshead 24 secured rigidly to the plunger bar 7, so that twice in each revolution of said wheel the plunger is raised, the spring 10 depressing it immediately upon its release by each of said 85 rollers.

To rotate the grooved wheel a large gear wheel 25 is also mounted in journaled relation to said wheel on shaft 5. The gear wheel is prevented from back rotation by a gravity pawl 25^a suitably mounted on a bracket 25^b carried by the standard 4. Wheel 25 meshes with a gear pinion 26 journaled on a stub shaft 27 secured to a lug 28 projecting from standard 4. A disk clutch member 29 is rotatable with the pinion and is provided with a plurality of ratchet shaped peripheral notches 30. A flanged disk 31 fits over the disk 29, and in conjunction with said disk and rollers 32 engaging the notches 30, constitutes a clutch. The clutch member 31 is rigid with a shaft 33 journaled on shaft 27 and provided with 100 105

an actuating handle 34. The handle, together with clutch member 31, may be turned in one direction inoperatively, but when turned in the reverse direction, that is as indicated by the arrow in Figure 2, adjacent the disk, will impart rotation to clutch member 29 and to the gear wheels 25 and 26, unless one of the pockets of wheel 21 contains a coin against which bears one of a pair of pins 35 projecting from the gear wheel 25, as will be readily seen by reference to Figure 5.

When the machine is at rest, it stands with wheel 21 in the position shown by Figure 5, so that its uppermost pocket shall be just below the lower end of a coin feed tube 36, whose upper end will be accessible for the reception of a coin, which coin will drop down in said tube until arrested by a pin 37 entering said tube through a slot 38 thereof, the pin 37 being carried at the upper end of a pivoted catch 39 mounted on a lug 40 projecting from the cap 3. After the coin is thus arrested, the operator through the actuating handle 34, imparts rotation to the gear wheel 25. The first result of this operation is to cause one of a pair of pins 41, projecting from the gear wheel 25, to press catch bar 39 rearwardly and thus withdraw its pin 37 from the path of downward movement of the coin to permit the latter to drop into the underlying pocket of wheel 21. As this occurs, the adjacent pin 35 of wheel 25, engages the coin and thereby imparts rotation to wheel 21, as indicated by the arrow in Figure 5. During a part of this movement, the coin is guarded against displacement from the pocket by the post extension 16, and just before a half revolution is completed the coin drops into the coin tube section 18 and down through the section 19 until arrested by a pin 43 projecting from a pivoted catch 44, a spring 45 connected to the lever and a bar 46 carried by plunger bar 7, normally holding the catch with its pin 43 in the path of downward movement of the coin. With a slotted or open coin tube as shown, the detention of the coin in section 19 will enable a person to see whether the coin which was instrumental in operation of the machine is spurious.

Pivottally carried by the crosshead 24 is a link 47 connected to the actuating arm 48 of a counter device 49 mounted with coin tube 36, on an arm 50 projecting from standard 4. It will thus be seen that with each upward movement, for example, of the crosshead, the counting device is operated, and with each downward movement of the crosshead the arm 48 is set for the next counting operation.

A pawl 51 pivotally pendent from the crosshead is disposed with its upwardly-facing tooth 52 adjacent to the face of an intermittently movable disk 53, the disk hav-

ing in this instance, four pins 54 disposed at equal distances apart and adapted to be successively engaged by the pawl 51, the arrangement being such that with each upward movement of the pawl the disk 53, is turned a quarter revolution, and that upon the downward movement of the crosshead and pawl, the latter is operatively disposed with relation to one of the pins 54, for the next turning movement of disk 53. The function of disk 53 is to operate a valve (not shown) in timed relation to the supply of compressed air to said valve, it being understood in this connection that the rollers 23 carried by disk 21, successively engage and elevate the crosshead, and that as each of such rollers passes over center with respect to the axis of disk 21, the tensioned spring 10 is free to effect the instant and rapid descent of the crosshead. In such descent the crosshead presses downwardly on the roller 23 which raises it, and thereby continues and accelerates the rotation of disk 21 until the other roller has attained a position in the same horizontal plane as the descending roller, and is engaged by the crosshead, which is therefore arrested as it attains its normal or depressed position. It will be understood that from the time an actuating roller 23 passes rearwardly over center, it is immaterial whether the operator of crank handle 34 continues such operation or not, as from such time, the balance of the half revolution described by disk 21 occurs automatically and cannot be prevented by the operator because the disk 21 bears a journaled relation with respect to the gear wheel 25 and hence to the handle 34.

The discharge for the intermittently compressed air passes through a flexible tube 73 having a tubular coupling 74 in communication with discharge port 14 of the cylinder 2, said tube 73 being connected to a discharge nozzle 75 which is adapted to eject fluid from a suitable container 76 by means shown in my copending application above-referred to or by means of the common and ordinary atomizer.

From the above description, it will be apparent that I have produced a device of the character described which possesses all of the features of advantage set forth as desirable, and while I have described and claimed the preferred embodiment of the same, I reserve the right to make all changes properly falling within the spirit and scope of the appended claims.

I claim:—

1. In a machine of the character described, a reciprocating crosshead, a cylinder having an air discharge port, a piston in the cylinder, a yieldingly-closed valve mechanism completely partitioning the cylinder between said port and the piston except when the latter is advancing, a crosshead

- movable with the piston, a disk provided with diametrically-opposite devices intermediate the said pockets for normally simultaneous engagement with the advance side of the crosshead and for alternately applying pressure on the latter to retract the same and the piston when the disk is turned a predetermined distance, means for automatically reversing the operation of the piston and crosshead to force air from the cylinder and cause the cross head by pressure on the disk-carried device which retracted the piston and crosshead, to continue the rotation of the disk until both of said devices are again in contact with the advance side of the crosshead, a coin tube for depositing a coin in the uppermost coin pocket when the disk is at rest, and means to apply pressure on such coin to turn the disk to retract the crosshead. 20
2. In a machine of the character described, a reciprocating crosshead, a cylinder having an air discharge port, a piston in the cylinder, a yieldingly-closed valve mechanism completely partitioning the cylinder between said port and the piston except when the latter is advancing, a crosshead movable with the piston, a disk provided with diametrically-opposite coin-receiving pockets and a pair of diametrically-opposite devices intermediate the said pockets for normally simultaneous engagement with the advance side of the crosshead and for alternately applying pressure on the latter to retract the same and the piston when the disk is turned a predetermined distance, means for automatically reversing the operation of the piston and crosshead to force air from the cylinder and cause the crosshead by pressure on the disk-carried device which retracted the piston and crosshead, to continue the rotation of the disk until both of said devices are again in contact with the advance side of the crosshead, a coin tube for depositing a coin in the uppermost coin pocket when the disk is at rest, and means to apply pressure on such coin to turn the disk to retract the crosshead. 30
3. In a machine of the character described, a reciprocating crosshead, a cylinder having an air discharge port, a piston in the cylinder, a yieldingly-closed valve mechanism completely partitioning the cylinder between said port and the piston except when the latter is advancing, a crosshead movable with the piston, a disk provided with diametrically-opposite coin-receiving pockets and a pair of diametrically-opposite devices intermediate the said pockets for normally simultaneous engagement with the advance side of the crosshead and for alternately applying pressure on the latter to retract the same and the piston when the disk is turned a predetermined distance, means for automatically reversing the operation of the piston and crosshead to force air from the cylinder and cause the crosshead by pressure on the disk-carried device which retracted the piston and crosshead, to continue the rotation of the disk until both of said devices are again in contact with the advance side of the crosshead, a coin tube for depositing a coin in the uppermost coin pocket when the disk is at rest, and means to apply pressure on such coin to turn the disk to retract the crosshead. 40
4. In a machine of the character described, mechanism for discharging liquid in atomized condition, an air pumping mechanism for effecting such discharge and atomization of the liquid and including a crosshead to be retracted and advanced, automatic means for effecting the advance of said pumping mechanism, a journaled disk having a pair of diametrically-opposite peripheral coin pockets, diametrically opposite means carried by the disk for simultaneous engagement with the advance side of the crosshead when the latter is at one limit of its movement, a wheel coaxial with said disk and provided with a pair of diametrically-opposite pins in proximity to the periphery of the disk and the rear sides, with respect to direction of rotation, of said coin pockets, a coin tube for guiding a coin into the uppermost pocket, means for rotating said wheel to cause one of said pins to engage the coin in the pocket and impart rotation to the wheel and retracting movement to said crosshead until the engaging means has passed over center with respect to the axis of the disk, to permit the automatic means to advance the pumping mechanism to perform its function and incidentally cause the crosshead, by pressure on said engaging means, to rotate the disk until the total movement of the latter equals a half revolution. 50
5. In a machine of the character described, mechanism for discharging liquid in atomized condition, an air pumping mechanism for effecting such discharge and atomization of the liquid and including a crosshead to be retracted and advanced, automatic means for effecting the advance of said pumping mechanism, a journaled disk having a pair of diametrically-opposite peripheral coin pockets, diametrically opposite means carried by the disk for simultaneous engagement with the advance side of the crosshead when the latter is at one limit of its movement, a wheel coaxial with said disk and 60

provided with a pair of diametrically-opposite pins in proximity to the periphery of the disk and the rear sides, with respect to direction of rotation, of said coin pockets, 5 a coin tube for guiding a coin into the uppermost pocket, means for rotating said wheel to cause one of said pins to engage the coin and impart rotation to the wheel and retracting movement to said crosshead until the engaging means has passed over center 10 with respect to the axis of said disk, to permit the automatic means to advance the pumping mechanism to perform its function and incidentally cause the crosshead, by pressure on said engaging means, to rotate the disk until the total movement of the latter equals a half revolution, and a coin tube 15 underlying the wheel for receiving the coin therefrom at about the moment the rotation of the wheel ceases.

6. In a machine of the character described, a disk provided with opposite peripheral coin pockets, means for normally holding the disk with the pockets respectively facing 20 upward and downward, a coin-supply tube for the upwardly-facing pocket and a coin tube for receiving a coin from the downwardly-facing pocket, a wheel coaxial with and bearing a journaled relation to said disk 25 and provided with a pair of diametrically- opposite pins in proximity to the periphery of the disk and the rear sides of said pockets respectively, with respect to the direction of rotation of the disk, means to turn said 30 wheel to cause its uppermost pin to engage a coin in the corresponding pocket and effect 35

the turning of the disk a quarter revolution, and means independent of said wheel, for continuing the rotation of said disk for another quarter revolution.

40

7. In a machine of the character described, a coin-supply tube and a coin-receiving tube, spring-actuated means for preventing coins dropping out of the coin-supply tube, a journaled disk between and in the plane of 45 said tubes and provided with diametrically- opposite coin pockets, a journaled wheel coaxial with said disk and provided with diametrically-opposite impelling pins paralleling and in the plane of the periphery of 50 the disk and respectively rearward, with respect to the direction of rotation, of the pockets of said disk, and for successive passage adjacent the discharge end of the coin-supply tube when the wheel is turned, and 55 pins projecting from said wheel for tripping the coin-holding means after the wheel is started on its rotation, to permit a coin to drop into one of said pockets and the path of the adjacent impelling pin and be engaged by the latter to effect a quarter revolution of said disk, and means independent of 60 said wheel, for continuing such movement of the disk for another quarter revolution to permit the coin to drop from the pocket into 65 the coin-receiving tube, and dispose the other pocket in position to receive the next coin from the coin-supply tube.

In witness whereof I hereunto affix my signature.

SAMUEL M. COFFMAN.
